UNITED STATES PATENT OFFICE.

EDMUND SCOTT GUSTAVE REES, OF WOLVERHAMPTON, ENGLAND.

ROTARY PUMP, CONDENSER, OR COMPRESSOR.

1,144,865.

Specification of Letters Patent. Patented June 29, 1915.

Application filed December 8, 1911. Serial No. 664,545.

To all whom it may concern:

Be it known that I, EDMUND SCOTT GUSTAVE REES, a subject of the King of Great Britain, residing in Wolverhampton, and whose post-office address is care of The Rees Roturbo Manufacturing Company Limited, of Wednesfield Road, Wolverhampton, in the county of Stafford, England, have invented certain new and useful Improvements in Rotary Pumps, Condensers, or Compressors, of which the following is a specification.

This invention is based upon the principle of the trompe or hydrostatic blowing engine, in which air is drawn into a downtake leading from a high level water reservoir by the velocity of water within the pipe and is entrained in the water which is divided or sprayed for this purpose near the upper end 20 of the pipe, the water and entrained air being delivered at a high pressure to a low level collector in which they are separated by suitable means and the compressed air led through a delivery pipe leading from the upper part of the reservoir to the place of storage or use while the water is discharged at the level of the collector or at a higher level. The present invention may be broadly described as the adaptation of this principle to a rotary apparatus in which centrifugal force is substituted for gravitational potential the requisite pressures and velocities being obtained by means of a rotary apparatus which comprises a rotary 35 pump which on its delivery side is designed to discharge a stream or streams of water adapted to entrain air or other gases and to discharge the water and entrained gases into one or more ducts which correspond with the downtake of the trompe and lead to a rotating water-sealed tank which corresponds with the collector or separator of the trompe. Leading inwardly from this tank toward the shaft is a duct or ducts corresponding with the uptake of the trompe and delivering the water to a fixed casing whence it is discharged to the atmosphere or to a second pump mounted on the same shaft and discharging through suitable nozzles into a fixed casing. 50 The entrained gas is separated under pressure from the water within the rotating collecting tank by the action of centrifugal force and is collected in an internal gas

space within the tank from which it is led to the place of use or storage by suitable means. 55

The invention is illustrated in the accompanying drawings wherein—

Figure 1 is a longitudinal section of one construction of rotary trompe according to this invention, Fig. 2 being a cross section of 60 which the left half is taken on line A—B, while the right half is on line C—D of Fig. 1; Fig. 3 is a longitudinal section showing a modified construction and Fig. 4 a similar view showing a further modification. 65

Referring first to Figs. 1 and 2 the impeller or rotary part *a* of the pump is, as shown, of the kind described in specification to British Letters Patent No. 4810 of 1906, receiving water through the inlet *b* from the suction pipe *c* and discharging it through a number of constricted nozzles or ducts *d* into a series of ducts *e* leading to a water-sealed collecting tank *f* contained within a rotating casing *g*. Air is drawn or forced into the streams of water within the ducts *e* by suitable means; for example, as shown, the constricted nozzles or outlet ducts *d* may be formed by introducing into the passages between each pair of adjacent 75 vanes *h* of the pump impeller a transverse pipe *i* which is open at one end to the atmosphere or to a space *j* connected with the chamber to be exhausted and has one or more lateral openings as for example, the saw-cuts *i* upon the farther side of the pipe in the direction of flow of the water from the pump impeller. The gas transpired through these orifices in the pipes *i* mingles and is entrained with the streams of water 80 and carried with them into the collecting tank *f*. It will be understood that any suitable means may be provided for spraying the water and facilitating the entraining of air or other gas thereby, as for example, the means described in my prior British Patents 22490/1906, 15084/1909 and 21555/1909. Also the pressure of the air entering the pipes *i* may be increased by means of a fan 85 rotating with the trompe as indicated in dotted lines at *r*, (Fig. 1), or the air may be delivered to the space *j* within the fixed casing by an independent blower mounted upon the trompe shaft or otherwise driven. 100

The entrained gas is separated from the 105 water within the collecting tank by ~~the no~~

tion of centrifugal force and is collected in an internal gas space j^o within the rotating tank g , which space is preferably arranged to communicate with a compressed air delivery pipe l through a hollow shaft k .

Leading inwardly toward the shaft from the collecting tank f is a series of ducts m which correspond with the uptake of the trompe and deliver the water to the water passages n within the fixed casing o , whence it passes through the discharge pipe p to the source of supply.

Alternatively, as shown in Fig. 3, the ducts m may deliver the water to the inlet of a second impeller a' which is preferably of the same character as the impeller a and is mounted on the same shaft and discharges the water through suitable nozzles d' into the fixed casing o , this second pump being provided, for example, for the purpose of annulling the hydrostatic balance between the two sets of ducts e and m of the water circuit leading to and from the collecting tank f or for the purpose of increasing the pressure of the water having the rotary trompe so as to deliver it to a cooling tower when, for instance, the trompe is used as a rotary jet condenser, or to a surface condenser when the apparatus is used for supplying cooling water to such a condenser, in which case the fixed casing of the trompe may be connected with the condenser in lieu of a dry air pump in such manner as to extract the air from the vacuum space.

The apparatus may be duplicated or otherwise multiplied, the various units being arranged to work in parallel or (so far as the water circulation is concerned) in series, drawing from the same source of water, and in the case of the parallel arrangement drawing from the same gas space and delivering to a common reservoir.

While the invention has been hereinbefore described more particularly with reference to its application to compressors it is to be understood that the same general arrangement may be adapted for the production of vacua in inclosed spaces or for condensing steam or other condensable gases or for purifying gases. In the last-mentioned case it is desirable to provide means for discharging the solid matter which may accumulate in the rotating tank constituting the collector or separator of the rotary trompe, and with this object as shown in Fig. 4, the tank may have provided at the periphery of the casing g a suitably constricted annular outlet or a series of nozzles such as g^o delivering to a suitably constructed duct or ducts g formed in the fixed casing o , the outlet of which ducts is provided with a valve r' which is normally closed but upon opening which any solid matter accumulated in the outer part of the rotating tank f can be blown out at intervals as required.

Having thus described the nature of this invention and the best means I know of carrying the same into practical effect, I claim:

1. A rotary pump, condenser or compressor based upon the principle of the trompe and comprising in one integral rotating structure a water pump member and ejector, a compressor and a collector, and means for introducing the gas or vapor to be entrained into the rotating structure near the periphery of the water pumping portion thereof.

2. A rotary trompe comprising a centrifugal water pump impeller connected with a water supply, an ejector device at the periphery of the water pumping portion of the impeller and connected with a gaseous fluid space, a centrifugal collector or separator into which the ejector discharges, the said impeller, ejector and collector forming an integral rotating structure, and means for discharging the uncondensed gases and the water separately from the collector.

3. A rotary trompe comprising, on one integral rotating structure a centrifugal pump and ejector, a water sealed tank rotating therewith, outwardly directed ducts leading from the ejector to the said tank, inwardly directed ducts leading from the water space of said tank, and a collecting pipe leading from the interior of the said tank.

4. A rotary trompe comprising a centrifugal ejector, a water sealed tank rotating therewith, outwardly directed ducts leading from the ejector to the said tank, an additional pump impeller rotating with the ejector and tank, inwardly directed ducts leading from the water space of said tank to the inlet of the additional impeller, and a collecting pipe leading from the interior of the tank.

5. A rotary trompe consisting of a rotary ejector and water sealed tank and means for discharging separately the water and gases collected in the tank, the said rotary ejector comprising a centrifugal pump impeller connected with a water supply, outwardly directed ducts leading from the impeller to the water sealed tank, and ejector nozzles constituted by transverse pipes open at one end placed in said ducts and having lateral openings thereto.

6. A rotary trompe comprising a rotary ejector having a series of mixing or entraining nozzles, rotating ducts leading from the said mixing nozzles and a rotating separating chamber into which the rotating ducts deliver.

7. A rotary trompe comprising a device adapted to entrain gaseous fluid in a mass of liquid by centrifugal force, said device being disposed and the admixture of gas and liquid being effected entirely within the ro-

tary apparatus, and a rotating collector wherein the liquid and the uncondensed gases are separated by centrifugal force.

8. An apparatus for evacuating spaces or for condensing or compressing gases, consisting of a rotary trompe having an impeller provided with a pressure chamber and constricted discharge nozzles, gas ducts leading to said nozzles, rotating ducts leading from said nozzles, said ducts always occupying the same position relative to said nozzles, and a rotating separating chamber

into which the rotating ducts discharge, the arrangement being such that the admixture of gas and liquid is effected entirely within ¹⁵ and the requisite pressures are entirely produced by the rotary apparatus.

In testimony whereof I have signed my name to this specification in the presence of two subscribing witnesses.

EDMUND SCOTT GUSTAVE REES.
